UNITED STATES PATENT OFFICE.

PHILIP T. DODGE, OF WASHINGTON, DISTRICT OF COLUMBIA, ASSIGNOR TO MERGEN-
THALER LINOTYPE COMPANY, A CORPORATION OF NEW YORK.

TYPOGRAPHICAL MACHINE.

1,076,409.

Specification of Letters Patent. Patented Oct. 21, 1913.

Application filed January 13, 1912 Serial No. 670,335.

To all whom it may concern:

Be it known that I, PHILIP T. DODGE, a citizen of the United States, and a resident of Washington, in the District of Columbia, have invented a new and useful Improvement in Typographical Machines, of which the following is a specification.

My invention relates to typographical composing machines, such as linotype machines of the general organization represented in Letters Patent of the United States, No. 436,532, to O. Mergenthaler, wherein circulating matrices are released from a magazine in the order in which their characters are to appear in print and then assembled in line together with expanding spacers, the composed line transferred to the face of a mold, the mold filled with molten metal to form a slug or linotype against the matrices which produce the type characters thereon, and the matrices thereafter elevated and returned through a distributing mechanism to the magazine or magazines from which they started.

More particularly, the invention relates to that class of typographical composing machines in which a series of magazines is employed and may be shifted to bring any selected one into operative relation to the assembling devices, as shown in my Letters Patent of the United States, No. 800,556.

In connection with movable magazines of the kind already referred to, I propose to employ adjustable means for conducting the type or matrices from the distributing mechanism to the magazine in operative position, and in the specific form illustrated and described, I use a single throat common to the several magazines, and provided with deflecting devices, such as switches, whereby the type or matrices are guided to any one of the magazines. In connection with such deflecting devices or switches, I preferably employ means whereby their movement and position are controlled by the shifting of the magazines in such manner that they are automatically governed to register with the selected one.

As previously indicated, the series of magazines is shiftably arranged, and in order to bring any one into operative relation to the assembling devices, I have provided mechanism which may be operated to effect the desired positioning thereof. Preferably the several magazines are independently and

detachably mounted in a common frame, so that each may be removed and replaced when desired to effect a change of font or face in the manner well understood in the art. In order to permit this removal and replacement of the individual magazines, the shifting means are so constituted that any desired one may be moved to a position beyond and free from the assembling devices, so that it may be readily manipulated; and I have also provided means to sustain the magazine during its removal or replacement, the said supporting means being so located that I am enabled to remove any magazine at the same level independently of and without disturbing the others.

These and other improvements are illustrated in the accompanying drawings in preferred form by way of example, and as applied to a linotype machine, but obviously many changes and variations may be made therein and in their mode of application without departing from the scope of the invention; and generally speaking, I desire it to be understood that I do not limit myself to any specific form or embodiment except in so far as such limitations are specified in the claims.

Referring to the drawings: Figure 1 is a transverse vertical section through the upper portion of a linotype machine having my invention applied thereto; Fig. 2 is a similar view showing the parts in different position; Fig. 3 is a sectional view taken substantially on the line 3—3 of Fig. 2; Fig. 4 is a sectional view taken substantially on the line 4—4 of Fig. 2; Fig. 5 is a sectional detail taken substantially on the line 5—5 of Fig. 2; Fig. 6 is a sectional view taken substantially on the line 6—6 of Fig. 2; Fig. 7 is a detached view on an enlarged scale of a portion of the throat and connected devices; Fig. 8 is a sectional detail taken substantially on the line 8—8 of Fig. 7; and Fig. 9 is a sectional view through the magazines, illustrating a modified arrangement.

Referring to Figs. 1 and 2 of the drawings, the distributing mechanism is or may be of the usual type, as set forth in the Mergenthaler patent previously referred to, or as used in the ordinary commercial linotype machine, and comprises the distributor bar or rail A, along which the matrices X are conveyed by the distributor screws A¹, until

they are released therefrom and pass through the throat or conducting means D into the appropriate channels of the magazine in use. In the present instance, I have shown three magazines, B, B¹, B², although any desired or convenient number thereof may be employed, and in order to permit them to be shifted so as to bring the selected one into operative position, I have arranged them in a frame C pivotally mounted on the framework at C¹, much in the same manner as set forth in my Letters Patent No. 800,556. It will be obvious that the frame C may be swung about its pivot C¹ so as to bring either magazine, B, B¹, or B² into operative relation to the face-plate E, through which the matrices descend to the further devices by which they are assembled in line, as in the ordinary linotype machine. The means for effecting the shifting of the magazines are specifically different from those illustrated in my said patent, and comprise in the present instance (see also Fig. 4) a hand-wheel G mounted upon the shaft G¹, which carries at its other end a bevel pinion G², meshing into a corresponding bevel pinion G³. The bevel pinion G³ is interiorly provided with a screw thread which engages with the screw G⁴, the latter passing freely through the supporting sleeve G⁵ and being formed with a slot or keyway G⁷ into which meshes a pin or feather (not shown) supported by the sleeve G⁵, the parts being arranged in such manner that the rotation of the pinion G³ effects the longitudinal movement of the screw G⁴ in the manner well understood in the art. The upper end of the screw G⁴ is preferably provided with a roller G⁶ upon which the frame C rests and whereby the frame and the magazines carried thereby are supported. The manipulation of the hand-wheel G, through the connections above described, effects the shifting of the magazines and enables any desired one to be brought into operative relation to the face-plate E. The wheel G may be provided with an operating handle G⁸, carrying the spring-pressed locking stud G¹¹ which is adapted to engage with a series of holes in the locking plate G¹², the holes being so located therein as to correspond with the several positions of the magazines. The stud G¹¹ is connected to the lever G⁹ pivoted at G¹⁰ to the handle G⁸, in such manner that when the handle is grasped to rotate the wheel G, the stud will be withdrawn from the plate G¹² and the magazines may be shifted to a different position. These shifting means may be employed not only for the purpose of bringing any desired magazine into operative relation to the assembling devices, but also to move it to a position above and free from the face-plate E, where it may be removed and replaced.

As previously indicated, the magazines B, B¹, and B², are independently and detachably mounted in the frame C. In the form illustrated, the frame and the magazines are located in inclined position and in such manner that when unlocked a magazine tends to slide downward and out of the frame by gravity. The means for detachably holding the magazines in position consist in the present instance of spring-pressed studs J (see Figs. 3 and 4) suitably mounted in the frame C and adapted normally to engage with the cross-bars J¹ of the magazines, which slide in the slots J² of the frame C.

In order to facilitate the removal of the magazines from the frame, I provide supporting and sustaining devices, such as the transverse rod or spindle H¹ (see Fig. 3) mounted in suitable bearings in the machine frame H and carrying one or more rollers H² adapted to engage and support a magazine during its passage to and from the magazine frame. I also provide at each side of the framework H the well-known hook or support H³ (see Figs. 1 and 2) adapted to engage the magazine cross-bars J¹ and to sustain the magazine and permit it to be tilted in the manner well understood in the art. It will be noted that the means for supporting the magazine in its passage to and from the frame, to wit, the spindle H¹, roller H² and hooks H³, are located in position to engage a magazine in a plane immediately above the face-plate E. The method of changing individual magazines will now be readily understood. The frame C is elevated to the desired extent in the manner previously described through the manipulation of the handle G⁸ and hand-wheel G, in order to bring the desired magazine to a position above and free from the face-plate E. The locking studs J are then moved out of contact with the magazine cross-bars J¹ and the magazine is then free to move forwardly and downwardly out of the frame C, (see Fig. 2), it being supported during its passage by the roller H² and if desired by the engagement of one of the cross-bars with the hooks H³ in the well-known manner. In replacing a magazine, the operation just described will be reversed. In this manner I am enabled to employ a single set of supporting devices in connection with a plurality of magazines, which are brought to the same level before they are removed from the frame or restored thereto.

In the form illustrated in Figs. 1 and 2, I employ a single series of escapements L, which operate in connection with the entrance channel L¹ communicating with the face-plate E. The escapements L are operated by the reeds L² in the customary manner, and are so mounted and arranged that in a condition of rest the matrices of the magazine in position are held thereby entirely within their channels and so that the

entrance L^1 contains no matrices. This disposition of the parts leaves the magazines free to be shifted without restoring any matrices thereto, as is sometimes necessary in certain types of machines.

Each of the magazines is provided with a device for locking the matrices therein before it is shifted to a new position, and in the present instance this consists of a rock shaft K , semi-circular in cross-section, and located in a suitable recess in the side of the magazine, in the manner well understood in the art. Normally the shaft K is so turned as to permit the free passage of the matrices from their channels, but before the magazines are shifted, the shaft is turned, as by the wrench K^1 (see Fig. 5) so as to cause the flat surface of the shaft to engage under the ears of the matrices, whereby they are locked securely in the magazine and whereby also they are moved upward to a limited extent within the channels so as to permit the shifting of the magazines without danger of their protrusion. The shaft may be held in this position by any suitable means, such as the pin K^2 .

In Fig. 9, I have shown a modified form wherein the provision of the locking devices last described becomes unnecessary. In this instance, a plurality of series of escapements M are employed, one in connection with each of the magazines and attached thereto, their position being such that the matrices X are held thereby entirely within the channels, so that the magazines may be shifted without the manipulation of other parts.

As previously indicated, the distribution of the matrices X is or may be effected by the customary distributor rail A and screws A^1 in such manner that they are delivered from the rail at the proper point to be transferred through the throat D to the appropriate magazine. In the present instance, a single throat is employed and constructed of such size and dimensions as to be common to all of the magazines, it being connected to the magazine frame C preferably by the transverse rod D^1 and in such manner that it partakes of the rotational movement of the magazines about their pivotal support C^1 . Referring more particularly to Figs. 6 and 7, the throat comprises two outer plates D^4 connected by a series of transverse partitions D^6 , which are secured to the plates D^4 in any suitable or convenient manner, as for instance by projecting lugs passing through corresponding openings in the plates and secured externally by a rod D^8 . The partitions D^6 divide the throat into a series of cells or passages corresponding to the magazine channels, their transverse extent being sufficient to permit the throat to communicate with all of the magazines. This construction renders necessary additional guiding means whereby the matrices

are delivered to the particular magazine in operative position, and for this purpose I preferably employ deflecting pieces or switches (two sets of such devices being shown in the present instance) which are automatically controlled by the movement of the magazines. In the form shown, these devices consist of comb-like structures, each comprising a web portion D^7 and switches D^2 or D^3 projecting therefrom between the several partitions D^6 of the throat. The web portions D^7 are mounted in recesses D^{10} and D^{20} formed in the plates D^6 of such size and form as to permit a limited angular movement of the webs therein. Connected to the web D^7 of the upper set are springs D^{14} so disposed as normally to hold the switches D^2 in their uppermost position, as shown in Figs. 2 and 7, and by dotted lines in Fig. 1. Similarly springs D^{15} connected to the web D^7 of the lower set hold the switches D^3 normally in their lowermost position, as shown by dotted lines in Figs. 1 and 7. In this relation of the parts, the matrices X passing from the rail A are deflected by and between the switches into the central magazine B^1 , as shown in Fig. 1.

When the lower magazine B or the upper magazine B^2 is brought into operative position, it is necessary to shift correspondingly the position of the deflecting switches, and this is accomplished in the following manner. The web D^7 of the upper set is formed with a transverse rock shaft D^8 carrying at its outer ends a pair of fingers D^{10} , and similarly the web of the lower set is provided with a transverse rock shaft D^9 carrying at its outer ends a pair of fingers D^{11} . Located in proximity to the fingers D^{10} and D^{11} and mounted upon the main frame of the machine are a pair of stationary projections or abutments D^{12} and D^{13} in position to engage the fingers D^{10} and D^{11} , respectively. When the frame C is moved downwardly so as to bring the magazine B^2 into operative position, the fingers D^{10} contact with the abutments D^{12} , thereby turning the web D^7 and connected switches D^2 against the force of the springs D^{14} until the switches D^2 reach their lowermost position in contact with and against the switches D^3 of the lower series, which are normally in engagement with the lower plate D^4 of the throat. In this position of the parts, the matrices delivered from the rail A pass above the switches D^2 and D^3 through the throat into the corresponding channels of the magazine B^2 .

When the frame C is moved in the opposite direction so as to bring the lower magazine B into operative position, the fingers D^{10} are relieved from the influence of the projections D^{12} and the springs D^{14} move the switches D^2 to their uppermost position, and simultaneously the fingers D^{11} of the

lower set are brought into engagement with the projections D^{13} whereby the switches D^s are swung against the force of the springs D^{16} into their uppermost position, substantially as shown in Fig. 2, it being obvious that the matrices will now be free to pass through the throat beneath both the switches D^s and D^e into the lower magazine B. In this connection, it is to be noted that due to its proximity to the pivotal point C¹, the angular movement of the upper portion of the throat is so slight as not to affect its operative relation to the distributing mechanism.

15. As previously described, when it is desired to remove the lower magazine B from the frame C, the latter must be elevated so that it will be brought above and free from the face-plate E, or, namely, to a position higher than the magazine occupies when it is in its operative relation to the face-plate. In the last mentioned position, as has already been pointed out, the switches D^s , due to the contact of the fingers D^{11} with the projections D^{13} , are already in their uppermost position in the throat, and the further movement required to bring the magazine B above the face-plate therefore necessitates a yielding connection or lost motion device, due to the contact of the fingers D^{11} with the projections D^{12} as the throat continues its movement. To this end, I connect the fingers D^{11} yieldingly to the rock shaft D^9 , as best illustrated in Figs. 7 and 8, wherein the said fingers are shown as loosely mounted upon studs D^{18} on the ends of the rock shaft D^9 and connected to the studs by springs D^{17} . These springs D^{17} are of sufficient strength to overcome normally the strength of the springs D^{15} at the time when the fingers D^{11} operatively engage with the projections D^{13} and without yielding. When, however, the switches D^s occupy their extreme position and it becomes necessary to move the throat still farther, the springs D^{17} will yield and permit the additional movement necessary to bring the magazine B to its uppermost position as shown in Fig. 2.

As previously stated, I have shown my invention in preferred form by way of example, but obviously there will be many changes and variations therein and in its mode of application which will suggest themselves to those skilled in the art and still be comprised within its spirit.

Having thus described my invention, its construction and mode of operation, what I claim and desire to secure by Letters Patent of the United States is as follows:

60. 1. In a typographical machine, the combination of a plurality of magazines, means for rendering any selected one thereof operative, a common delivery throat for the magazines, and devices controlled by the

said means for directing the type or matrices from said throat into the operative magazine.

2. In a typographical machine, the combination of a plurality of magazines, means for rendering any selected one thereof operative, a common delivery throat for the magazines, and a deflector situated within the throat and controlled by the said means for directing the type or matrices from said throat into the operative magazine. 75

3. In a typographical machine, the combination of a plurality of magazines, means for rendering any selected one thereof operative, distributing mechanism, a common delivery throat for connecting the distributing mechanism with all the magazines, and a plurality of deflectors situated within the throat and controlled by the said means for directing the type or matrices from the distributing mechanism into the operative magazine. 80

4. In a typographical machine, the combination of a plurality of magazines, means for rendering any selected one thereof operative, a common delivery throat for the magazines, and devices controlled by the said means for causing the type or matrices to traverse different paths in their passage through the throat corresponding to the magazine in operation. 95

5. In a typographical machine, the combination of a plurality of movable magazines, and common adjustable means for delivering type or matrices to any selected one thereof, said means being controlled in its operation by the movement of the magazines. 100

6. In a typographical machine, the combination of a plurality of magazines movable to bring a selected one into operative position, a common delivery throat for said magazines, a plurality of deflectors situated within the throat, and means for adjusting said deflectors to cause them to direct the type or matrices into the magazine in operative position. 110

7. In a typographical machine, the combination of distributing mechanism, a plurality of magazines movable to bring a selected one into operative position, and common adjustable means controlled by the shifting of the magazines for connecting the distributing mechanism with the selected magazine. 115

8. In a typographical machine, the combination of distributing mechanism, a series of magazines shiftable to bring a selected one into operative position, and means carried by the said series of magazines and movable relatively thereto and controlled by the shifting of the magazines to connect the distributing mechanism with the selected magazine. 120 125

9. In a typographical machine, the combination of distributing mechanism, a plurality of shiftable magazines, a delivery throat, a switch movably mounted in said throat, and means whereby the switch is controlled by the shifting of the magazines to connect the distributing mechanism with the operative magazine.
10. In a typographical machine, the combination of a plurality of shiftable magazines, a common throat therefor, movable switches therein, and abutments whereby the movement of the switches is controlled by the shifting of the magazines.
11. In a typographical machine, the combination of relatively fixed assembling devices, a plurality of inclined magazines shiftable vertically with reference thereto and each independently removable in a forward direction over the assembling devices, and means whereby any selected magazine may be shifted to clear the assembling devices to permit its removal.
12. In a typographical machine, the combination of a plurality of inclined magazines shiftable vertically and each independently removable in a forward direction at one and the same level, relatively fixed means for supporting and sustaining the selected magazine during its removal at such
- level, and means for shifting the selected magazine to the level of removal.
13. In a typographical machine, the combination of assembling devices, a plurality of inclined magazines shiftable vertically with relation thereto and each independently removable in a forward direction over the assembling devices, stationary means located above the assembling devices to sustain the magazines during removal, and means for shifting the magazines to bring any selected one thereof in position for removal.
14. In a typographical machine, the combination of a plurality of inclined magazines shiftable vertically and each independently removable in a forward direction, stationary devices for sustaining the magazines during removal, and means for shifting the magazines relatively to the stationary devices to bring any selected one thereof into position for removal.

In testimony whereof I hereunto set my hand this 5th day of January, 1912, in the presence of two attesting witnesses.

PHILIP T. DODGE.
